UNITED STATES PATENT OFFICE.

WILLIAM S. LORD, JR., OF PORTLAND, MAINE.

DESIGN FOR A KEY-RING AND BOTTLE-SEAL BREAKER.

SPECIFICATION forming part of Design No. 33,634, dated December 4, 1900.

Application filed October 22, 1900. Serial No. 33,971. Term of patent 14 years.

To all whom it may concern:

Be it known that I, WILLIAM S. LORD, JR., a citizen of the United States, and a resident of Portland, in the county of Cumberland and State of Maine, have invented and produced 5 a new and original Design for a Key-Ring and Bottle-Seal Breaker, of which the following is a full, clear, and exact description.

Reference is to be had to the accompanying 10 drawings, forming a part of this specification, in which similar characters of reference indicate corresponding parts in both views.

Figure 1 is a side elevation of a key-ring and bottle-seal breaker embodying my design, and Fig. 2 is a sectional view of the 15 same on the line 2 2 in Fig. 1.

The design comprises the curved top members *a*, the upper extremities of which converge toward each other and are projected

downward, presenting essentially the shape 20 of a heart.

The design further embodies a member *c*, with an upwardly-projecting central portion, the member *c* presenting the appearance of a plate or web extending between the sides of 25 the bottom part *b* of the device.

Having thus described my invention, I claim as new and desire to secure by Letters Patent—

The design for a key-ring and bottle-seal 30 breaker, as herein shown and described.

In testimony whereof I have signed my name to this specification in the presence of two subscribing witnesses.

WILLIAM S. LORD, JR.
